[57] **CLAIM**

The ornamental design for a self-contained solar heating system module, substantially as shown and described.

DESCRIPTION

FIG. 1 is a front perspective view of the self-contained solar heating system module showing my new design;

FIG. 2 is a back elevation view thereof;

FIG. 3 is a right side elevation view thereof, the undisclosed left side is the same in appearance as the side shown;

FIG. 4 is a top plan view thereof;

FIG. 5 is a front elevation view thereof; and

FIG. 6 is a bottom plan view thereof.

Fig. 1.

Fig. 2.

Fig. 3.

Fig. 4.

Fig. 5.

Fig. 6.
